(57) **CLAIM**

The ornamental design for a spray gun trigger, as shown and described.

DESCRIPTION

FIG. 1 is a perspective front view of the spray gun trigger, which embodies my design; FIG. 2 is a perspective rear view thereof; FIG. 3 is a bottom view thereof; FIG. 4 is a top view thereof; FIG. 5 is rear view thereof; FIG. 6 is front view thereof; FIG. 7 is a left side view thereof; FIG. 8 is a right side view thereof; FIG. 9 is a perspective view thereof mounted on a spray gun; and, FIG. 10 is a side view thereof mounted on a spray gun. The broken line showing of a spray gun is included for the purpose of illustrating environment and forms no part of the claimed design.

1 Claim, 4 Drawing Sheets
